Application June 9, 1939, Serial No. 278,249

5 Claims. (Cl. 36—57)

This invention pertains to footwear and relates more particularly to shoes of the pump type and to a novel method of making them, the invention having for its principal object the provision of a pump of practical and commercially acceptable construction having its throat portion so designed as to minimize any tendency of the edge of the upper material to bite into the wearer's foot.

10 Prior attempts to attain the above or similar objects have ordinarily involved a necessary and substantial departure from usual methods of production, with a concomitant distinctive and sometimes inartistic or otherwise undesirable appearance in the finished shoe. The present invention makes it possible to obtain the desired functional characteristics in a shoe which need not noticeably differ in appearance, at least to the casual observer, from standard commercial

15 types of shoe.

Moreover such prior attempts have usually involved constructions such that the effect sought after, if attained at all, was confined to a limited area at the most forward part of the throat opening. However, the part of the foot which is most sensitive to pressure is located approximately at the inner front corner of the throat opening, one of the larger nerves being near the surface of the instep at this point and overlying the substantially unyielding phalangeal bone. In prior constructions, as often as not, there is an actual thickening and stiffening of the upper material at this very point where flexibility and yieldability are most to be desired. In accordance with the present invention no such thickening of the upper material occurs at this point and the elastic yield of the upper may readily be extended to include the inner corner (or both corners) of the throat opening thereby insuring the utmost comfort at the place most needed.

In the accompanying drawings wherein one desirable embodiment of the invention is illustrated by way of example:

45 Fig. 1 is a perspective view of a shoe of the pump type embodying the invention;

Fig. 2 is a plan view of the inner surface of a vamp useful in making the improved shoe;

50 Fig. 3 is a plan view of a length of tape employed in making the improved shoe;

Fig. 4 is a section to large scale on the line 4—4 of Fig. 3;

Fig. 5 is a section on the line 5—5 of Fig. 3;

55 Fig. 6 is a plan view showing the outside surface of the vamp and illustrating one of the

early steps in the process of making the improved shoe, the vamp being shown as opened out flat for convenience in illustration;

Fig. 7 is a view of the inside of the vamp illustrating the next successive step in the process, the vamp being shown opened out flat;

Fig. 8 is a fragmentary section to large scale on the line 8—8 of Fig. 7;

Fig. 9 is a similar section on the line 9—9 of Fig. 7;

Fig. 10 is a plan view showing the inside of the upper as it appears at the completion of the operation, the upper being opened out flat;

Fig. 11 is a view showing the appearance of the outside surface of the upper at the completion of the throat forming operation, the upper being opened out flat;

Fig. 12 is a section to large scale on the line 12—12 of Fig. 11;

Fig. 13 is a similar section on the line 13—13 of Fig. 11.

Fig. 14 is a fragmentary plan view of a piece of composite bead-forming tape of a modified construction;

Fig. 15 is a fragmentary transverse section through the edge of the upper, illustrating the first step in the use of the tape of Fig. 14;

Fig. 16 is a section similar to that of Fig. 13, but illustrating the use of the tape shown in Fig. 14;

Fig. 17 is a view similar to Fig. 12, but illustrating the use of the tape of Fig. 14; and

Fig. 18 is a fragmentary section, to large scale, on the line 18—18 of Fig. 1.

Referring to the drawings, the numeral 1 designates a shoe of the pump type embodying the present invention. This shoe comprises the upper 2, the sole 3, and the heel 4. The top edge of the upper is provided with a finish B, for example of the kind known as a French-cord

edge, which extends uninterruptedly around the entire periphery of the top of the upper (including the throat end of the foot-receiving opening T) and which is of substantially uniform external appearance at all points. However, al-

though this edge finish is of substantially uniform appearance, it is to some extent elastically stretchable at the front of the throat opening, although at other points it is substantially in-

extensible.

In preparing this edge finish or bead B in accordance with the present invention, it is preferred to proceed substantially as follows: Re-

ferring to Figs. 3, 4 and 5, a composite bead-

forming strip, comprising two lengths of tape 6

and 7 is first prepared. The lengths of tape 6 and 7 are of substantially equal width except as hereinafter referred to and of substantially the same length, the length of the two pieces 5 being such as to permit them to extend completely around the top edge of the upper of the shoe and to provide a slight overlap at the points where their ends are joined. The tape 6 is the outer or finish tape, and in accordance with the 10 present invention is preferably elastically stretchable,—consisting of a length of rubber-elastic webbing including textile material of such a nature and being of such a fabric construction, for example woven or braided, as to 15 provide the desired exposed surface finish and appearance in the completed shoe. The lining tape 7 may be of any desired material, usually a textile narrow fabric, and is substantially inextensible. These lengths of tape are disposed in 20 contact with each other with their longitudinal edges in registry and are preferably united by adhesive, as indicated at 8 (Fig. 4). That part of the inextensible lining tape 7 which will extend around the forward end F of the throat opening T, is substantially reduced in width so as to form an elongate recess or cutout portion 9 terminating at the points 10 and leaving a very 25 narrow section 7a of this lining tape overlying one margin only of the elastic tape 6 at this 30 point.

Referring to Fig. 2, which shows the inside of a conventional one-piece vamp 2a, it may be noted that the edge 11 of this vamp is that which defines the top edge of the shoe upper and which 35 also defines the throat end of the foot-receiving opening T. As a preliminary step, the margin of the vamp at the throat may be furnished, if desired, with a reinforce strip 12. This reinforce strip, if used, is preferably of elastically stretchable material and may be secured to the inner 40 side of the vamp by means of adhesive. However, the provision of this reinforce strip is optional, and it may be omitted if desired. At this stage in the process, the vamp may be closed at 45 the heel in any usual manner, although for convenience in illustration herein, the vamp is shown opened out flat.

Having prepared the composite strip 5 of finish forming material, this strip is now disposed 50 against the outside surface of the vamp as illustrated in Fig. 6 so as to extend along the top edge 11 of the upper and around the throat, the strip 5 being so disposed that the tape 6 contacts the vamp and so that at the throat end of the 55 foot-receiving opening the narrow part 7a of the lining tape is spaced from the edge F of the vamp, leaving only the elastically stretchable tape 6 to register with the edge F. The strip 5 is now secured to the vamp by a sewed seam 13 which is disposed as close to the edge 11 of the 60 vamp as it is practicable to do, the ends of the strip being slightly overlapped at an inconspicuous point, usually just forward of the heel at the inner side of the shoe.

65 The composite strip 5 is now turned over the top edge 11 of the vamp as illustrated in Figs. 7, 8 and 9, so that the free marginal portion of this strip is disposed at the inside of the vamp. This marginal portion of the strip 5 is now preferably secured to the inside surface of the vamp 70 by means of adhesive 14 (Fig. 8). In thus turning the strip 5 over the top edge 11 of the vamp, the strip 5 is made to assume a more or less rounded bead-like form of smooth arcuate curvature in transverse section, as illustrated in Figs. 75

8 to 16, it being noted that the strip is not drawn down so tightly over the edge 11 as to prevent this smoothly rounded and attractive bead-like appearance.

The shoe lining L is of usual materials and of substantially usual pattern, except that at the front of the throat opening the margin of the lining is recessed so that the top edge of the lining is spaced further from the top edge of the outer element of the upper than at other points. 10

The upper margin of this lining is now lapped over the turned margin of the composite strip 5, as illustrated in Figs. 12 and 13, and the parts are secured together by a sewed seam 15 which extends through the several thicknesses of material and permanently joins them together. Except as hereinafter pointed out, this seam is placed near enough to the top edge of the outer element of the upper so that it is substantially concealed at the outside of the upper by the 20 bulging lower portion of the bead B. However, in passing around the throat end of the foot-receiving opening, this seam is spaced farther away from the top edge of the vamp, following the recessed margin of the lining, as indicated at 15a, 25 so that at this point it does not impose substantial restriction upon the stretch of the bead-forming material.

As will be noted from comparison of Figs. 12 and 13, the effective portion of the finish bead B 30 at the throat opening consists solely of the extensible tape 6, since the upper edge 16 of the narrow band 7a of the inextensible tape is spaced a substantial distance below the top edge 11 of the vamp, whereas at other points in the shoe 35 the finish bead B comprises both the extensible tape 6 and its associated inextensible tape 7. It will further be observed that at the front of the throat opening, where the seam 15a is spaced a substantial distance from the top edge 11 of the 40 upper, the upper material is allowed to stretch within its normal capabilities and this degree of stretch of the upper material at this point, coupled with the permissible stretch of the tape 6 at this point, provides the requisite yieldability 45 of the shoe upper at the front of the throat opening to prevent any cutting of the wearer's foot by the edge of the upper material at this point. However, at other points along the edge of the upper, the seam 15, together with the inextensible tape 7, substantially prevents stretch of the upper material so that the shoe preserves its lasted shape as well or even better than shoes finished in the ordinary manner. 50

In order to avoid the necessity of forming the 55 recess or cutout 9 in the individual strip of the bead-forming tape, it is contemplated that tape such as shown in Fig. 14 may be used. This composite tape is made in any desired length. From this material appropriate lengths to extend around the top edge of the shoe are cut off as desired. This composite tape 5x includes the elastically stretchable tape 6x and the relatively inextensible textile 7x, these tapes being united by means of adhesive, it being noted that the tape 6x is substantially wider than the tape 7x so that its marginal portion M is free to stretch and contract.

In applying this composite tape 5x to the shoe upper, the exposed margin M of the composite 70 tape (Fig. 15) is placed in registry with the top edge of the outer member 2a of the upper and is secured thereto by the sewed seam 13x. The composite tape is then folded over the top edge of the upper so that its free margin lies against 75

the inner surface of the upper to which it may be secured by means of adhesive. The upper part of the lining L is then lapped over this marginal portion of the composite tape (Fig. 16) 5 and the parts are united by means of the sewed seam 15^x which is placed very close to the rolled outer margin R of the tape 6^x and which follows the top edge of the lining very closely.

At the front of the throat opening the top 10 edge of the lining is spaced farther from the top edge of the outer member of the upper than at other points, as may be seen by comparison of Figs. 16 and 17. Thus in causing the sewed seam 15^x to follow the top edge of the lining, the 15 seam is spaced farther from the top of the outer member 2^a of the upper at the front of the throat opening than at other parts. Whereas the seam 15^x firmly unites the elastic member 6^x, the inelastic member 7^x, and the relatively inelastic 20 lining at points closely adjacent to the top edge of the outer member of the upper around the sides and back of the shoe, this seam 15^x is substantially spaced from the top edge of the outer member of the upper around the forward edge of 25 the throat opening. The stretchable member 6^x is thus allowed to stretch quite freely at the front of the throat opening without being opposed in its stretch by its engagement with the lining, and since the inextensible tape 7^x is substantially narrower than the extensible tape 6^x, the tape 7^x does not take part in the formation 30 of the rolled exposed portion of the edge bead and thus does not substantially oppose stretch of the latter at the front of the throat opening. 35 However, at other parts, where the seam 15^x passes through this extensible member 7^x and the lining, the exposed part of the bead is substantially inextensible.

By reference to Fig. 18 it will be evident that 40 in attaining the objects of the invention the shoe upper is not abnormally thickened at the front corners of the throat opening, thus avoiding painful pressure upon the nerves of the foot such as has resulted from some prior constructions designed to provide elasticity at the front 45 of the throat opening.

It is to be noted that the provision of the stretch or yield at the front of the throat opening in accordance with the present invention does not necessitate any substantial difference 50 in appearance of the edge finish or bead at this point,—the only visible difference being that the seam 15 drops slightly below the bead at the forward edge of the throat opening so as to become visible. As this seam is not conspicuous, a shoe embodying the present invention, although 55 possessing the desired stretch at the front of the throat opening, is hardly distinguishable to the ordinary person from a shoe of the same style not embodying this improvement.

While certain desirable embodiments of the invention have been illustrated by way of example, it is to be understood that the invention is not necessarily limited to these precise embodiments nor to the particular materials referred to, but is to be regarded as broadly inclusive of any equivalent construction or of substitute materials such as fall within the terms of the appended claims.

70 I claim:

1. A shoe of the pump type having an upper and a finishing bead extending uninterruptedly around the entire top edge of the upper, including the throat portion, said bead being of substantially uniform appearance throughout, the

bead comprising an extensible element and an inextensible element, each of said constituent elements of the bead extending uninterruptedly from the back of the pump along one side, around the throat end of the foot-receiving opening, and 5 thence along the opposite side to the back of the pump, said inextensible element being so constructed and arranged relative to the extensible element as to prevent stretching of the extensible element except in the vicinity of the throat end 10 of the foot-receiving opening.

2. A shoe of the pump type having an upper and a finishing bead extending uninterruptedly around the entire top edge of the upper, including the throat end of the foot-receiving opening, 15 said bead being of substantially uniform appearance throughout, the bead comprising an outer finishing tape of elastic material and a lining tape of substantially inelastic material, said tapes being of substantially uniform width except at 20 the throat end of the foot-receiving opening where the inelastic tape is reduced in width through the provision of a cut-out in the edge nearest to the edge of the upper thereby to permit the elastic tape to stretch at the throat end of the foot- 25 receiving opening.

3. A shoe of the pump type having an upper and a French-cord finishing bead extending uninterruptedly around the entire top edge of the foot-receiving opening, said bead comprising a 30 substantially inextensible lining tape and a relatively extensible outer tape, said tapes being anchored along one edge to the outer surface of the shoe upper except that at the throat end of the foot-receiving opening the lining tape is 35 cut in from the secured edge thereof and is unsecured to the upper, the tapes being turned over the top edge of the shoe upper so that the lower marginal portions of the tapes are disposed at the inner side of the upper, and a sewed seam 40 uniting said lower marginal portions of the tapes to the shoe upper, said seam extending close to the top edge of the upper except along the throat end of the foot-receiving opening where it is spaced forwardly from the edge of the upper, 45 the lining tape being effective to prevent stretch of the outer tape except at the throat end of the foot-receiving opening.

4. A shoe of the pump type having an upper and a French-cord finishing bead extending uninterruptedly around the entire top edge of the throat opening, said bead comprising a pair of 50 flexible tapes of substantially the same width disposed in registry with one another, one of said tapes being a substantially inextensible lining tape and the other being an elastically stretchable outer tape, a sewed seam uniting said tapes along one edge to the outer surface of the shoe upper near the top edge of the latter, the lining tape being so reduced in width at the 55 throat end of the foot-receiving opening that it is not caught in said sewed seam, the tapes being turned over the top edge of the upper so that the marginal portions of the tapes are disposed at the inner side of the upper, and a sewed seam 60 uniting said marginal portions of the tapes to the shoe upper, said latter seam being located closely adjacent to the top edge of the upper except at the throat end of the foot-receiving opening where it is substantially spaced from 65 said edge although engaging both tapes.

5. A shoe of the pump type having an upper and a composite strip of flexible material forming a finishing bead which extends uninterruptedly around the entire periphery of the top 75

- of the upper, said strip comprising a pair of tapes each of such length as to extend all of the way around the foot-receiving opening of the shoe, one edge of one of said tapes being in 5 registry with one edge of the other tape throughout their entire lengths, one of said tapes being a substantially extensible lining tape and the other tape being an elastically stretchable outer tape, a sewed seam uniting one edge of the 10 stretchable tape, at least, to the outer element of the shoe upper close to the top edge of the latter, the lining tape being of such lesser width than the outer tape, at least at the throat end of the foot-receiving opening, that at the throat 15 end of said opening said lining tape is not caught in said sewed seam, the composite strip curling

over the edge of the upper to form a rounded bead with the registering edges of the two tapes disposed at the inner side of the upper, said last-named registering edges of the two tapes being spaced from the top edge of the shoe 5 upper, and a second sewed seam uniting said latter registering edge portions of the two tapes to the shoe upper, said second seam being so closely adjacent to the top edge of the outer element of the upper as to be substantially concealed by the bulge of the bead except at the throat end of the foot-receiving opening where it is substantially spaced from the top edge of the upper although engaging both tapes. 10
